UNITED STATES PATENT OFFICE.

SAMUEL TRACHTENBERG, OF CLEVELAND, OHIO.

COMB ATTACHMENT.

Application filed October 11, 1923. Serial No. 667,900.

To all whom it may concern:

Be it known that I, SAMUEL TRACHTENBERG, a citizen of the United States, residing at Cleveland, in the county of Cuyahoga and 5 State of Ohio, have invented certain new and useful Improvements in Comb Attachments, of which the following is a specification.

This invention is an attachment for a comb more particularly the pocket comb 10 type and has for an object to provide means whereby a mirror or the like may be removably carried upon the back edge of the comb.

Another object is to provide an attachment 15 of this character which includes clips adapted to straddle the back edge of the comb and retain removably a mirror upon the comb, the clips being frictionally engaged and consequently quickly removable.

It is likewise an object to provide an attachment of this character in which the mirror 20 is insertable prior to mounting upon the comb and in which the clips and mirror or frame are formed from a single strip of sheet metal substantially inverted U-shaped in 25 cross-section.

Other objects will be in part obvious and in part pointed out hereinafter.

In order that the invention and its mode 30 of operation may be readily understood by persons skilled in the art, I have in the accompanying illustrative drawings, and in the following detailed description based thereon, set out one possible embodiment of the same.

In these drawings:

Fig. 1 is a side elevation showing my attachment arranged upon the back of the comb.

Fig. 2 is a side elevation showing the frame slightly extended for the insertion of 40 the mirror shown below said frame.

Fig. 3 is an end elevation of the assembled comb and attachment, and

Fig. 4 is a central vertical section in detail showing the manner of retaining the 45 mirror in its frame.

Having more particular reference to the drawings throughout which similar characters of reference designate similar parts, this attachment includes a pair of spaced clips 5 which as shown are substantially U-shape in 50 cross-section and adapted to straddle the end portions of the comb back and to frictionally engage therewith, said clips being con-

nected at their inner ends by an outwardly bowed frame 6, which is formed to removably 55 retain the mirror 7 or other insert.

This attachment is adapted to be formed from flexible metal and the strip at its intermediate portions is reduced in width for the formation of the said frame 6, which as 60 shown in Fig. 4 is substantially inverted U-shape in cross-section whereby to form a channel for the reception of the edge of the insert.

As is clearly indicated in Fig. 1, the mirror 65 and its frame are positioned upon the comb resting snugly upon the back edge of the comb and due to the gripping action of the clips 5, the attachment is securely retained in position. It is understood that the frame 70 6 may be formed in any desired shape for the reception of different types of inserts.

Due to the fact that this attachment is 75 formed from a single strip of sheet metal and requires very little labor in its manufacture, the expense will of course be comparatively small. These attachments are adapted to retain the mirror 7 or other insert prior to its being positioned upon the comb, thus providing an article which may 80 be marketed for use upon combs already being used.

Manifestly, the construction shown is capable of considerable modification and such modification as may fall within the scope of 85 my claims, I consider within the spirit of my invention.

I claim:

1. A comb attachment comprising an insert, a frame adapted to receive portions of 90 the edges of the insert, and a pair of oppositely directed clips carried by the frame and adapted to frictionally engage the comb back and retain the insert upon the back.

2. A comb attachment including an open 95 frame, an insert and a pair of oppositely directed clips carried by the frame and extending from the lower outer ends of the frame formed integrally therewith and adapted to straddle the outer portions of the 100 comb back to retain the insert in the frame.

3. A comb attachment of the character described including spaced spring clips adapted to frictionally engage the outer portions 105 of a comb back edge, an outwardly bowed flexible frame connecting the inner ends of

the clips, and a mirror removably retainable in the frame.

4. A comb attachment of the character described formed from a strip of sheet metal substantially inverted U-shape in cross-section, an intermediate portion of said strip being of less width than the remaining portions, an outwardly bowed flexible frame

formed from the intermediate portion, a mirror removably insertable in the bowed frame and attaching clips formed by the end portions of the strip and adapted to frictionally engage the comb back edge. ¹⁰

In testimony whereof, I affix my signature.

SAMUEL TRACHTENBERG.
